(57) **CLAIM**

The ornamental design for a laryngoscope blade, as shown and described.

DESCRIPTION

The patent or application file contains at least one drawing executed in color. Copies of this patent or patent application publication with color drawing(s) will be provided by the Office upon request and payment of the necessary fee.

FIG. 1 is a side view of a laryngoscope blade embodying the design of the present invention;

FIG. 2 is the other side view of the laryngoscope blade of FIG. 1;

FIG. 3 is a top view of the laryngoscope blade of FIG. 1;

FIG. 4 is a perspective side view of the laryngoscope blade of FIG. 1;

FIG. 5 is a further side perspective view of the laryngoscope blade of FIG. 1;

FIG. 6 is a further perspective view of the laryngoscope blade of FIG. 1;

FIG. 7 is an end view of the laryngoscope blade of FIG. 1;

FIG. 8 is a reverse perspective view of the laryngoscope blade of FIG. 1;

FIG. 9 is a further perspective view of the laryngoscope blade of FIG. 1; and,

FIG. 10 is a further side view of the laryngoscope blade of FIG. 1.
